UNITED STATES PATENT OFFICE.

MARK GUY, OF NEW YORK, N. Y., ASSIGNOR TO JOHN MCCLAVE & SONS,
OF SAME PLACE.

DESIGN FOR A JOINT-LUG FOR BICYCLE-FRAMES.

SPECIFICATION forming part of Design No. 25,591, dated June 2, 1896.

Application filed October 14, 1895. Serial No. 566,693. Term of patent 7 years.

To all whom it may concern:

Be it known that I, MARK GUY, a subject of the Queen of Great Britain, residing in the city, county, and State of New York, have 5 invented, created, and produced a new and original Design for Joint-Lugs for Bicycle-Frames and the Like, of which the following is a specification.

My new design relates to the shape of joint-lugs for bicycle-frames, and comprises as its 10 distinctive features new shapes for the vertical or upright and lateral or inclined members of such joint-lugs.

The new design is shown in the accompanying 15 drawings, in which—

Figure 1 is a side elevation of a joint-lug for a bicycle-frame embodying the features of the new design, and Fig. 2 is a top plan view thereof.

Referring to the drawings, A is the upright 20 tubular member, and B the lateral or angular tubular member, of a joint-lug for a bicycle-frame. The member A is internally and externally cylindrical and has parallel top and 25 bottom ends extending in planes at right angles to its axis, these ends being lettered a and b, respectively. The wall c of the member A is externally smooth and cylindrical. The lateral member B is also internally 30 and externally cylindrical and has an upper end d, which merges into the wall of the member A at e, a lower or outer end f, and an intermediate smooth cylindrical wall g.

The distinctive features of my new design 35 reside in the shape of the member A and in the shape of the outer end of the member B.

According to the new design the member A has like cylindrical portions C at top and bottom and an intermediate recess or aperture D, separating the portions C and having 40 a curved wall h of substantially semicircular shape when viewed from the side of the joint-lug. The wall h is substantially opposite the junction of the lateral and upright members and approximates in its outline the reverse 45 of the line e of junction between the members A and B.

According to another feature of the new design the lower or outer end of the member B is bifurcated by a tapering recess E and 50 terminates in two tapering points F F. The walls of the recess E consist of a sharp half-circle i at the inner or upward extremity of the recess near the longitudinal middle of the member B, then opposite gradual convex 55 curves j, diverging from the curve i and meeting a short and substantially semicircular curve k, terminating the ends F of the member B.

The new design gives an attractive and 60 graceful appearance to the joint-lug.

What I claim is—

The design for a joint-lug for bicycle-frames and the like, substantially as shown and described. 65

In witness whereof I have hereunto signed my name in the presence of two subscribing witnesses.

MARK GUY.
